FIG. 1

FIG. 2

FIG. 3

FIG. 1 is a front elevational view of a light emitting gas discharge matrix display panel showing our new design, it being understood that the wires are continuous throughout the center of the panel as indicated, the rear being identical to the front shown with the gas fill tubulation turned 90 degrees;

FIG. 2 is an elevational view taken from one side thereof, the opposite side being a mirror image of the side shown; and

FIG. 3 is a bottom plan view thereof, the top being a mirror image of the bottom shown.

We claim:

The ornamental design for a light emitting gas discharge matrix display panel, as shown and described.
